UNITED STATES PATENT OFFICE.

CHARLES BIENZ, OF ST. JEAN, GENEVA, SWITZERLAND.

SLIDE VALVE.

1,411,153.

Specification of Letters Patent. Patented Mar. 28, 1922.

Application filed September 27, 1921. Serial No. 503,670.

To all whom it may concern:

Be it known that I, CHARLES BIENZ, a citizen of the Republic of Switzerland, residing at St. Jean, Geneva, in the Republic of Switzerland, have invented certain new and useful Improvements in Slide Valves, of which the following is a specification.

The present invention relates to slide valves for gas engines, such as internal combustion engines, explosion motors and steam engines.

In order to more clearly understand the invention reference is made to the accompanying drawings which show by way of example two embodiments of the object of the present invention.

Fig. 1 is a longitudinal section of a first embodiment.

Fig. 2 is a longitudinal section of a second embodiment.

According to the first embodiment, the valve consists of a slide *a*, adapted to travel over the outer wall *b* of the cylinder *c*, in which the piston *d* moves. This slide valve *a* is adapted to close the port *e*, is provided with an inclined face *f* and is housed in a casing, one face of which has a corresponding slope and is arranged in a sleeve passing through two guides *h* and *i* attached to the walls of the cylinder *c*.

This sleeve *g* is traversed longitudinally from end to end by a stem *j* connected to one end of the connecting rod *k* worked by the motor. A spiral spring *l* surrounds the second extremity of the stem *j*, abutting on one side against a double nut *m* screwed on the stem *j* and on the other side against the bottom of the housing provided in the sleeve *g*. The cap nut *n* is screwed on the sleeve *g* and bears against a shoulder *o* provided on the stem *j*.

Assuming that the members of this valve occupy the position shown in the drawing, and that at the moment the connecting rod *k* is moved in the direction of the arrow *p*, the stem *j* is drawn by this movement and the spring *l* is compressed; thus reacting on the sleeve *g*, the inclined face of which bears against the inclined face *f* and consequently the slide valve is pressed against the outer wall *b* of the cylinder thereby progressively closing the port *e*. This closing

effect after having attained a maximum, subsequently diminishes until the shoulder *o* abuts against the cap nut *n*, that is to say 55 when the connecting rod *k* has accomplished half a revolution.

If at that moment the movement of the connecting rod *k* always takes place in the direction indicated by the arrow *p*, the shoulder *o* making contact with the cap nut *n* pushes the sleeve *g*, the result being to cause the slide *a* to travel along the outer wall *b*. When this movement takes place, the spring *l* not being in tension, there is 65 no pressing of the slide *a* against the wall *b*.

After having reached the end of its stroke, the slide *a* moves in the opposite direction over the wall *b*, so as to take up the position shown in the drawings.

The cycle of movements is repeated as above described.

According to the second embodiment the valve consists of a slide *a'* adapted to travel over the outer wall *b'* of the cylinder *c'*, 75 in which moves the piston *d'*. This slide *a'* intended to close the port *e'* is provided with an inclined face *f'* and housed in a casing, one face of which has a corresponding slope and is arranged in a sleeve *g'* 80 passing through two guides *h'* and *i'*, fixed to the walls of the cylinder *c'*. Into this sleeve *g'* passes a stem *j'* attached at one end to the slide *a'*. A spiral spring *p'* surrounds the other end of this stem *j'* and 85 bears on the one side against a double nut *m'* screwed on the stem *j'*, and on the other hand against the bottom of the housing provided on the sleeve *g'*, the result being to keep the slide *a'* in position against the 90 wall *b'*.

An adjusting nut *n'* screwed into the sleeve *g'* connects the latter to a connecting rod *k'* actuated by the motor.

Assuming the members of this valve to 95 occupy the position shown in the drawings, and that at the moment the connecting rod *k'* is moved in the direction of the arrow *p'*, the sleeve *g'* is drawn by this movement and the slide *a'* is moved, whereupon the 100 port *e'* is alternately closed and opened.

What I claim and desire to secure by Letters Patent is:—

In combination in an engine, a cylinder,

a port in said cylinder, a reciprocating valve therefor adapted to cover and uncover said port, comprising a triangular slide and means to actuate said slide including a 5 wedge shaped member to engage said slide, said cylinder being provided with means for

holding the slide adjacent to said port during additional movement of said actuating means whereby said slide is pressed against said port.

10

In testimony whereof I affix my signature.

CHARLES BIENZ.
